ADJUSTING CONNECTOR FOR
CLOTHESLINES

Warren E. White, Forest Hills, N. Y.

Application September 9, 1947, Serial No. 772,997

4 Claims. (Cl. 211—119.15)

1

My invention relates to an adjusting connector for clotheslines, and the like.

An important object of the invention is to provide an adjusting connector for clotheslines, the use of which will eliminate the tying of knots in the clothesline, each time it is tightened or loosened.

A further object is to provide a clothesline connector which is positive in action, not permitting a tightened clothesline to slip, and having means to engage the clothesline without cutting or weakening the same.

A still further object is to provide a device of the above mentioned class, which is simple and durable in design, and quite inexpensive to manufacture.

Other objects and advantages of the invention will be apparent during the course of the following description.

In the accompanying drawings, forming a part of this application, and in which like numerals are employed to designate like parts throughout the same,

Figure 1 is a side elevation of a clothesline connector embodying my invention, and showing the associated clothesline,

Figure 2 is an enlarged plan view of the same,

Figure 3 is a central vertical longitudinal section taken on line 3—3 of Figure 2,

Figure 4 is a horizontal section taken on line 4—4 of Figure 3,

Figure 5 is a transverse vertical section taken on line 5—5 of Figure 3,

Figure 6 is a fragmentary vertical section taken on line 6—6 of Figure 3,

Figure 7 is a perspective view of a clamping member, removed, and

Figure 8 is a vertical detail section through a clothesline tensioning roller.

In the drawings, where for the purpose of illustration is shown a preferred embodiment of the invention, the numeral 10 designates the outer casing of the clothesline connector. This casing 10 is elongated, and rectangular in transverse cross section. The casing 10 includes a bottom 11, sides 12, an end 13, and a partial top 14. The top 14 extends longitudinally of the casing for a short distance from the end 13, and is connected to such end and to the sides 12 to form a box like structure. The remainder of the top of the casing is open, beyond the inner edge of the top 14, and the other end of the casing is also open. The sides 12 are preferably curved at the open end of the casing as shown in Figures 1 and 3. The bottom 11 of the casing is provided

2

near its longitudinal center with a transverse opening or slot 15, preferably extending for the full width of the casing. The transverse edges of the slot 15 are rolled to provide rounded beads 16, to prevent cutting a clothesline section 17, which is passed through the slot. The bottom 11 also has an opening 18, to receive the end of the clothesline section 17, which is knotted, as at 19. The knot 19 is disposed inside the casing 10, and is larger than the opening 18, so that it cannot be pulled through such opening. The casing end 13 has a central opening 20, like the opening 18, and the end of a second clothesline section 21 is passed through this opening and knotted within the casing, as at 22. The knot 22 is larger than the opening 20, so that it cannot be pulled through such opening.

Disposed between the casing sides 12, adjacent to the open top and end portion of the casing is a pivoted clamping member or arm 23. This clamping arm 23 is in the shape of an inverted U, in transverse cross section, and includes a top 24, and sides 25, pivotally connected to the casing sides 12, near their curved ends, by means of pins 26, or the like. The sides 25 incline upwardly toward the top 24, at one end, and are curved correspondingly to the casing sides 12 at their opposite ends. The pivoted clamping arm 23 is open, longitudinally, but further comprises a flat bottom or clamping foot 27, integral with the sides 25, and adjacent to their lower edges. The transverse edges of the clamping foot 27 are rolled to provide rounded beads 28, which cannot cut the clothesline. The pivot pins 26 are preferably in approximate horizontal alignment with the clamping foot 27, Figure 3. Rotatably mounted upon a shaft 29, rigidly secured to the sides 25, and extending laterally between such sides, is a roller 30. The ends of the shaft 29 are flush with the outer faces of the sides 25, so as not to interfere with the swinging of the arm 23. The roller 30 is located substantially directly over the bead 28 which is nearest the open end of the outer casing 10.

A rubber pad or strip 31 is mounted upon the casing bottom 11, beneath the clamping foot 27, and the clothesline section 17 engages upon this pad. The pad 31 is secured in place by a rivet 32, or the like.

Arranged near the inner end of the arm 23, and pivotally mounted in opening 33 in the casing sides 12, is a U-shaped strap or clamp 34. This clamp 34 swings vertically, and is adapted to engage over the inner end of the arm 23, to clamp the same in a closed or clamping position. The

top 24 may be provided with one or more lateral corrugations 35, to receive the top of the U-shaped clamp 34, when the same is in the clamping position, Figure 3.

The arm 23 is provided at its top with a lateral projection or handle 36, preferably stamped out of the adjacent side 25, see Figure 7. This handle facilitates opening and closing the clamping arm 23.

It is preferred that the casing 10 and clamping arm 23 be fabricated as sheet metal stampings, and the parts are well adapted to be made as such.

In use, the sections of clothesline are attached to the outer casing 10, as shown and described. The clothesline section 17 is passed through the slot 16, beneath the clamping foot 27, and up over the roller 30, as shown in Figure 3. The clamping arm may be swung upwardly to its open position, where it does not clamp the clothesline. The slack may be removed from the clothesline section 17 downwardly through the slot 15, Figure 3, and forming the loop 17'. When the line is taut, the arm 23 is swung to the closed or clamping position, Figure 3. The clamping foot 27 clamps the clothesline against the rubber pad 31, in tight clamping engagement, so that the clothesline cannot slip. The arrangement of the clothesline over the roller 30 further helps to prevent slipping; and when the arm 23 is swung closed, the roller 30 gives an added tension to the clothesline section 17, exteriorly of the device. The clamp 34 locks the arm 23 in the clamping position.

It should be noted that there are no sharp edges or knurled wheels, and the like to engage the clothesline, and damage the same. The device is positive in its clamping action, and very useful for the desired purpose.

It is to be understood that the form of my invention, herewith shown and described is to be taken as a preferred example of the same, and that various changes in the shape, size and arrangement of parts may be resorted to, without departing from the spirit of the invention, or the scope of the subjoined claims.

Having thus described my invention, what I claim is:

1. An adjusting connector for clotheslines, comprising an outer casing open at its top and including an end having an opening and a bottom having openings therein, a clamping arm arranged within the outer casing and pivotally connected therewith to swing from an open to a closed position, such clamping arm including a presser foot having its edges rounded and adapted to engage upon the clothesline to clamp the same against the bottom of the casing when the arm is in the closed position, a roller mounted upon the arm above the presser foot for engaging the clothesline to tighten the same when the arm is swung to the closed position, and means to secure the arm in the closed position, the arrangement being such that the end of one clothesline is fastened within the opening in the end of the casing, and a second clothesline is fastened within one opening in the bottom and passed through the other bottom opening and beneath the presser

foot and over the roller, such second clothesline being adjustable while the arm is in the open position.

2. An adjusting connector for clotheslines, comprising an outer casing open at its top and at one end and including sides, an end having an opening, and a bottom having an opening and a slot provided with rounded edges, a friction element mounted upon the casing bottom, a U-shaped clamping arm disposed between the casing sides adjacent to its open top and open end and pivotally connected with the casing sides near its bottom and open end, said clamping arm including a lower flat clamping foot having rounded transverse edges, said foot being arranged near and above the friction element when the arm is in a clamping position, a transverse roller mounted within the U-shaped clamping arm and disposed above the foot, and a pivoted clamp carried by the casing near one end of the clamping arm to engage over the arm and lock the same in the clamping position.

3. An adjusting connector for clothesline sections comprising an outer U-shaped casing open at the top and one end, means for connecting the adjacent ends of said clothesline sections to said outer casing, an inverted U-shaped clamping arm, a pivot pin pivotally connecting said clamping arm to said outer casing at said one end, a presser foot on said clamping arm for clamping one of said clothesline sections within said casing, a transverse roller in said clamping arm above and inwardly of said pivot pin over which the clothesline section under said presser foot is adapted to be engaged, and means for securing said clamping arm in clothesline clamping position in said casing.

4. An adjusting connector for a pair of clothesline sections comprising an outer member, means for securing an end of one of said clothesline sections to said outer member, a clamping arm, a pivot pin at one end of said member engaging said clamping arm for swinging movement longitudinally thereof, a presser foot on said clamping arm adjacent said pivot pin for clamping an end of the other clothesline section on said outer member, a transverse member across said clamping arm above and inwardly of said pivot pin and the outer end of said presser foot, over which said other clothesline section is adapted to be engaged, and means carried by said outer member engageable with said clamping arm for locking said clamping arm and said presser foot in clamping position.
